UNITED STATES PATENT OFFICE.

HENRY M. MYERS, OF BEAVER FALLS, PENNSYLVANIA.

BLANK FOR SHOVELS.

SPECIFICATION forming part of Letters Patent No. 340,603, dated April 27, 1886.

Application filed February 10, 1885. Renewed October 22, 1885. Serial No. 180,634. (No model.)

To all whom it may concern:

Be it known that I, HENRY M. MYERS, of Beaver Falls, in the county of Beaver and State of Pennsylvania, have invented a certain new and useful Improvement—to wit, a new article of manufacture—a Blank for the Making of Shovels; and I do hereby declare that the following is a full, clear, and exact description thereof, reference being had to the accompanying drawings, and to the letters of reference marked thereon.

In the manufacture of shovels, particularly that class known to the trade as "plain-back shovels," it has been the practice to take a bar 15 of iron or steel and cut it into the ordinary form for a shovel-blank, or when made of cast-steel to cast the blank, which blanks are heated, then plated under the hammer or rolled to the desired width, length, and thickness 20 for the purpose of forming the shovel-blade and handle-straps, which are trimmed by the shearing process to the desired contour.

The ordinary form of blanks have always been in their width much narrower than the 25 width of the shovel-blade when plated or rolled, so that in the plating or rolling of the blank it had to be drawn or forged out lengthwise and laterally, which operation had a tendency to draw the fiber or particles of the iron or 30 steel asunder, thereby weakening the shovel-blade, which is particularly the case when made of iron or what is known to the trade as "Bessemer steel;" hence it is common to find shovels, when thus constructed, cracked or 35 split lengthwise of the shovel-blade after having been subjected to strain in their use.

It is a well-established fact that the fiber of the iron or the polarity of the axis of particles of the steel in the working of the iron or steel 40 in the forging or rolling process is always in line with the angle of force applied to the blank.

The object of my invention is to furnish the trade with a blank for the manufacture of 45 shovels, scoops, and spades of such construction that it may be reduced to the desired length and thickness for the formation of the shovel-blade and the handle-straps by the rolling process, so that the fiber of the iron or the 50 longitudinal axis of the particles of steel will always be lengthwise of the shovel-blade and handle-straps, and not drawn or forced asun-

der laterally, thereby giving strength to the shovel-blade and handle-straps, and diminishing the cost in the manufacture of shovels. 55

To enable others skilled in the art to which my invention is most nearly connected to make and use it, I will proceed to describe its construction and operation.

In the accompanying drawings, which form 6c part of this specification, Figure 1 represents in perspective a bar of iron or steel. Fig. 2 represents in perspective a blank for the manufacture of a shovel-blade and its handle-straps when cut from the bar shown in Fig. 1. 65

In the making of my new article of manufacture I roll a billet of iron or steel into a bar of the form shown in Fig. 1, which should be of the requisite width and thickness for forming the blank for the shovel-blade and handle-straps, so that said bar may be cut into a series of blanks of the form shown in Fig. 2, whereby said blanks are made without loss of material, excepting that portion of the bar marked A, as indicated by the dotted lines in Fig. 1, 75 which blank is cut from the bar by a suitable cutting-machine, the construction of which is left to the skill of those familiar with the construction of metal-cutting machinery.

The blank shown in Fig. 2 from the point 80 D to the point C is within a fraction of an inch equal to the width of the shovel-blade when plated or rolled down to the desired thickness, and the length of the arm E corresponds to the length desired for the handle-straps. 85

In the plating or rolling process the metal of the blank is drawn out in the direction indicated by the arm marked E.

The essential feature and novelty of my new article of manufacture consists in having that 90 portion of the blank marked F from the point D to the point C about equal to the width of the shovel-blade, which is new in the art of making shovel-blanks, and by which construction of blank the manufacturer is enabled to 95 reduce the blank to the desired thickness, length, and width for the shovel-blade and handle-straps by the rolling process, the blank passing between the rolls always in the direction of the arm marked E, thereby having the 100 fiber of the iron or the longitudinal axis of the particles of steel running lengthwise of the shovel-blade and handle-straps without the tendency of drawing the said fiber or said par-

ties asunder laterally, whereby a much stronger shovel is made, which will finish with greater ease and finer polish, and the shovel as a whole manufactured at diminished cost 5 with comparatively unskilled labor, and the shovel in its use will have a tendency to retain a smooth surface.

Having thus described my invention, what I claim is—

10 As a new article of manufacture, a shovel,

scoop, or spade blank of the form shown in Fig. 2, in which the part marked F from the point D to the point C is substantially equal to the width intended for the shovel-blade, as herein described, and for the purpose set forth.

HENRY M. MYERS.
